DUAL AUDIO-EDUCATION DESK

MacLean W. Briggs, Wichita, Kans., assignor to The
Advance Furnace Company, Wichita, Kans., a corpo-
ration of Kansas

Filed Aug. 3, 1960, Ser. No. 61,622

Term of patent 14 years

(Cl. D33—7)

FIG. 1

FIG. 2

FIG. 3

FIG. 4

FIG. 5

FIG. 6

FIG. 7

Fig. 1 is a three-quarter rear perspective view of a dual audio-education desk embodying my design, with both desk tops in open position;

Fig. 2 is a three-quarter front perspective view of the desk shown in Fig. 1;

Fig. 3 is a top plan view of the same;

Fig. 4 is an end view of the same;

Fig. 5 is a three-quarter rear perspective of the desk shown in Fig. 1 with the desk tops in closed position;

Fig. 6 is a view similar to Fig. 2 with the desk tops in closed position; and

Fig. 7 is a fragmentary enlarged view of a portion of one of the three sound absorbing panels.

I claim:

The ornamental design for a dual audio-education desk, substantially as shown, and described.
